Attorney

UNITED STATES PATENT OFFICE.

CORNELIO E. CASACLANG, OF DETROIT, MICHIGAN.

MOISTENING DEVICE.

Application filed January 11, 1926. Serial No. 80,594.

My present invention has to do with the moistening of stamps, envelope flaps and the like; and it contemplates the provision of an efficient device, adapted to be carried with facility in the pocket, and calculated to enable a user to quickly and easily apply an adequate amount of moisture to a stamp or to an envelope flap for the fastening thereof.

10 Other objects and practical advantages of the invention will be fully understood from the following description and claims when the same are read in connection with the drawings, accompanying and forming part 15 of this specification, in which:—

Figure 1 is a view, partly in elevation and partly in section, illustrative of the preferred embodiment of my invention.

Figure 2 is a transverse section taken in 20 the plane indicated by the line 2—2 of Figure 1.

Similar numerals of reference designate corresponding parts in both views of the drawings.

25 Among other elements my novel device comprises a cylindrical casing 1, preferably of hard rubber, closed at one end as designated by 2, and open at its opposite end. Carried within the casing is a compressible

30 water container 3 of soft vulcanized rubber and possessed of resiliency, the said water container being closed at one end and open at its opposite end and adapted at the latter end to be sprung upon a closure plug 4 so as to yieldingly maintain the connection between itself and the said plug. The plug 4 is preferably of hard rubber and is maintained in position in the casing 1 by frictional contact, or may, in the discretion of

40 the manufacturer, be threadedly secured in the casing 1. The said closure plug is provided with a central orifice 5 and with a valve seat 6 at the inner end of said orifice 5, and it is also provided with a guard 7,

45 the latter to limit the inward movement of a valve 8 on which is a stem 9 that extends through the orifice 5 and a considerable distance beyond the plug 4, Figure 1. At 10 is a section of sponge or equivalent material, the said section 10 being cup-shaped—i. e., closed at its forward end and open at its rear end, and being adapted to be used as a direct applying element for moisture, the scheme of my invention contemplating 55 the supply of water from the tube 3 to the

interior of the applying element 10 whereby the said element 10 will be impregnated with water and will be adapted to adequately moisten a stamp or the adhesive bearing portion of an envelope flap or the like. The 60 open end of the element 10 surrounds the forward reduced portion of the closure plug 4, and is retained on said portion by a surrounding resilient band 11, preferably of vulcanized rubber; the said band being interposed between the plug 4 and the cylinder 1 so that the element 10 will be reinforced and held in proper working position by the cylinder or casing 1. The guard 7 has for its function to prevent undue opening movement of the valve 8, and it also serves to prevent displacement of the said valve 8 as when the device is carried in the pocket with the sponge element 10 uppermost.

75 The valve 8 is preferably of appropriate rubber, and when the device is carried in the pocket with the sponge element 10 lowermost, the weight of water in the tube 3 will operate by pressure to maintain the valve 8 in closed position so that the passage of water from the tube 3 to the sponge element 10 will be prevented.

75 An opening 11^x is formed in the side wall of the casing 1, and in said opening 11 is positioned a lever 12, the long arm of which is adapted to be pulled outwardly and then pushed inwardly. The short arm of the lever 12 is disposed against a pressure member 13 located alongside of and in contact with the compressible tube 3. Manifestly by tending to spring outwardly the tube 3 acting through the pressure member 13 will serve to yieldingly maintain the long arm of the lever 12 in the normal position illustrated in Figure 1. It will be noticed however, that the long arm of the lever 12 may be pulled outwardly against the yielding resistance of the tube 3, and that the said operation will be attended by compression of the tube 3 so that when the long arm of the lever 12 is released the tube 3 will expand and in that way operate to draw water through the sponge element 10 and the orifice 5 and past the valve 8 into the tube 3. 100 From this it follows that by immersing the sponge element 10 in a glass of water or the like, pressing downwardly upon the sponge element 10 if necessary, the interior of the tube 3 may be supplied with water 110

by moving the long arm of the lever 12 outwardly and inwardly.

It will be apparent from the foregoing that my novel device is of such character that a cap similar to that employed on a fountain pen may be used in association with my novel device, the cap being arranged over the sponge element 10 and detachably secured by frictional contact or otherwise on the adjacent end of the casing 1, and the said cap being equipped with a clip analogous to the kind employed on ordinary fountain pen caps. I have, however, deemed it unnecessary to illustrate the said cap as the same does not form part of my invention.

It will be appreciated that when equipped with a cap such as indicated, my novel device may be conveniently carried in the pocket, and that when it is desired to use the device it is simply necessary to remove the same from the pocket, displace the said cap and then apply the sponge element 10 to the stamp, envelope flap or the like to be moistened, and in this connection it will be noticed that when the sponge element 10 is subjected to pressure it will act against the stem 9 of the valve 8, and by displacing the said valve 8 will permit the passage of water from the tube 3 to the interior of the sponge element 10, and the said sponge element 10 becoming impregnated with water will operate to adequately apply sufficient water to the adhesive bearing surface for the adequate moistening of the adhesive.

Manifestly when the sponge element 10 is relieved of pressure, the weight of the water will operate to close the valve 8 and enable the same to prevent passage of water from the interior of the tube 3 to the interior of the element 10.

It will be understood from the foregoing that my device may be made in various sizes within the discretion of the manufacturer, and that in no case is it necessary to make the device so large as to render the same cumbersome and unfitted to be carried in the pocket after the manner of a fountain pen.

It will also be appreciated that notwithstanding the capacity of function ascribed to my novel device, the same is simple and inexpensive in construction, and is susceptible of being embellished in the same manner as a fountain pen or the like so as to constitute an attractive appurtenance to be carried in the pocket.

I have specifically described the preferred embodiment of my invention in or-

der to impart an understanding of the said embodiment in all of its details. I do not desire, however, to be understood as confining myself to the specific construction and relative arrangement of parts as disclosed, my invention being defined by my appended claims within the scope of which changes in structure and arrangement may be made without departure from my invention.

Having described my invention, what I claim and desire to secure by Letters Patent, is:—

1. A moistening device comprising a casing closed at one end and open at its opposite end and having an opening in its side wall, a resilient compressible tube arranged in the casing and closed at one end and open at its opposite end, a pressure member located alongside of and in contact with the tube, a lever disposed in the said opening in the side wall of the casing and having one of its arms arranged in engagement with the said pressure member, a closure plug for the open end of the casing and upon which the compressible tube is secured of itself, said closure plug having an eduction orifice and a valve seat at the inner end thereof and also having a valve guard, a rectilinearly movable valve opposed to said valve seat and interposed between the same and the said guard and having a stem extending forwardly through the said orifice and beyond the same, an absorbent applying member closed at its forward end and open at its rear end and enclosing the said valve stem and adapted to cooperate therewith and having its rear open end arranged about the closure plug, and a resilient band surrounding the said open end of the applying element and detachably holding the same on the closure plug and arranged within the open end of the casing.

2. The combination in a moistening device, of a water container, a closure therefor having an eduction orifice and a valve seat at the inner end thereof, a valve opposed to said seat and having its stem extending through and beyond said orifice, and a flexible, cup-shaped absorbent applying element enclosing the valve stem and movable to cooperate with said stem and open the valve and secured with respect to the closure means.

In testimony whereof I affix my signature.

CORNELIO E. CASACLANG.
